(57) **CLAIM**

The ornamental design for a media system, as shown and described.

DESCRIPTION

FIG. 1 is a front, right, and top perspective view of a hub of a media system embodying the new design and illustrating the hub in a first configuration with a cover slid open for camera or other sensor operation;

FIG. 2 is a rear, left, and bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right, and top perspective view of the hub in a second configuration with the cover slid closed to cover a camera or sensor and prevent camera or sensor operation;

FIG. 10 is a front elevational view thereof;

FIG. 11 is a rear elevational view thereof;

FIG. 12 is a left side view thereof;

FIG. 13 is a right side view thereof;

FIG. 14 is a top plan view thereof;

FIG. 15 is a bottom plan view thereof;

FIG. 16 is a front, right, and top perspective view of a mount of the media system embodying the new design and illustrating the mount in a closed configuration;

FIG. 17 is a rear, left, and bottom perspective view thereof;

FIG. 18 is a front elevational view thereof;

FIG. 19 is a rear elevational view thereof;

FIG. 20 is a left side view thereof;

FIG. 21 is a right side view thereof;

FIG. 22 is a top plan view thereof;

(Continued)

FIG. 23 is a bottom plan view thereof;
 FIG. 24 is a front, right, and top perspective view of the mount in an open configuration;
 FIG. 25 is a front and bottom perspective view of the hub of FIG. 1;
 FIG. 26 is a right side view of the hub of FIG. 1 connected to the mount of FIG. 16 and illustrating the hub in a first position;
 FIG. 27 is a right side view of the hub of FIG. 1 connected to the mount of FIG. 16 and illustrating the hub in a second position;
 FIG. 28 is a front, right, and bottom perspective view of the hub of FIG. 1 connected to the mount of FIG. 24 and illustrating the hub in a third position; and,
 FIG. 29 is a front, right, and bottom perspective view of the hub of FIG. 1 connected to the mount of FIG. 24 and illustrating the hub in a fourth position.
 The broken lines are shown for the purpose of illustrating portions of the media system or portion thereof and/or environmental matter and form no part of the claimed design. The dot-dash broken lines define the bounds of the claimed design and form no part thereof.
